HIGH VOLTAGE OIL SWITCH

Application filed July 13, 1927, Serial No. 205,300, and in Czechoslovakia July 10, 1926.

In high voltage oil switches it is desired to increase the efficiency and the reliability of the switch by increasing the rapidity of the switching operation. The reason for this is that the duration of the arc occurring in the switching operation depends upon the rapidity of movement of the switch proper and further that it is desired to reduce the generation of hot oil vapours to a minimum. However in the oil switches as heretofore constructed increase in the rapidity of the switching operation is impossible in view of the large masses which must be moved, with the result that undue shocks take place and necessitate undesirably great power for actuating the switch.

The object of this invention is to provide a high voltage oil switch, which provides for a great rapidity of the switching operation while requiring only comparatively small power for operating the same, and which is efficient in operation and durable in construction. These objects are accomplished by means of the present invention and by coupling the driving element of the oil switch with the driven element by coupling devices comprising a clutch having lost motion and a resilient element, cooperating with each other, said resilient element adapted to be tensioned in consequence of the inertia of the driven part, whereby the clutch is adapted to accumulate energy and suddenly transmit such energy to said driven element at the moment when the inertia of the driven part is overcome. According to the invention the construction of the switch is such that the accumulation of the actuating energy transmitted is effected partly in kinetic and partly in a potential form and a sudden transmission of the energy accumulated to the driven element is made possible.

In the drawings two constructional forms of the high voltage oil switch embodying the invention are shown by way of example. Fig. 1 shows a vertical central section of a switch, Fig. 2 is a section on the line II-II Fig. 1, Fig. 3 is a vertical central section of the driving mechanism of another constructional form, Fig. 4 is a plan view of a brake mechanism, Fig. 5 shows a time-way graph and Fig.

6 is a plan view of the entire oil switch provided with the brake mechanism.

In Fig. 1, 1 denotes an oil vessel and 2 denotes the insulators passing through and secured to the cover 3 of the switch, the insulators being provided with the contact pieces 4 at their bottom ends. The contact member 6 is constructed as a hollow body of aluminum or the like and is rotatable around a vertical axis. The contact member 6 is insulated from the switch casing by a cylindrical tube 7 of insulating material attached to the contact member by means of a clamping sleeve 8. Another clamping sleeve 8' establishes the connection with the switch shaft 10 through a part 9.

A casing 11, made in two parts and separated from each other by a horizontal joint, is secured to the cover 3 and fully encloses the driving mechanism. The switch shaft 10 carries at its top end an inverted dish shaped body 13 detachably secured thereto and provided at its bottom side with teeth 14" (Fig. 2) resembling those of a clutch 14. The teeth 14' engaging between the teeth 14" are provided on a part 15 surrounding the switch shaft 10 and journaled in the casing 11 by means of a ball bearing 16, the part 15 carrying at its top side a dished projection 17. The bottom side of the part 15 carries gear teeth 18 on a part of its circumference into which a toothed segment 21 engages, the latter being disposed at the end of a lever 20. The lever 20 is pivoted on the cover of the switch by means of a journal pin 22 and is actuated by a pulling device 23 pivoted to the lever 20 by a journal pin. A powerful coiled spring 25 is interposed between and abutting the parts 13 and 17.

The operation of the driving mechanism of the switch is as follows: The movement of the pulling device 23 is transmitted to the lever 20 and the toothed segment 21. Therefore the part 15 to which one end of the coiled spring 25 is connected is rotated and the spring 25 is put under tension, the teeth 14' of the clutch (Fig. 2) being moved in the direction of the arrow p. Between the teeth 14' of the part 15 and the teeth 14" of the part 13 there is provided a space s which pro-

vides lost motion and results in the teeth of the clutch coming into mesh with each other after having moved through the said space *s*. Simultaneously with the engagement of the 5 teeth 14' and the teeth 14'', the driving mechanism imparts movement to the driven part, that is to say, to the switching shaft 10, the parts 9, 8, 7 and the contact member 6. The acceleration of the driven part is brought 10 about by the sudden disengagement of the tensioned spring 25 and by the direct transmission of the movement by means of the clutch 14. It is important in this connection that during the movement through the space 15 *s* an accumulation of the energy of the driving mechanism takes place in two ways, i. e., first by the moved masses of the driving mechanism (kinetic energy) and second by the 20 spring 25 put under tension during the movement through the space *s* (potential energy). Because of the step by step acceleration of the masses to be driven, in the first step up to the throwing into operation of the clutch 14, the parts 15, 20, 23 and in the second step, the 25 parts 13, 10, 8, 7, 6 being accelerated, the result is secured, according to the present invention, that with an equal switching force the contact member moves rapidly away from the contact 4 and thus the voltaic arc is prevented from staying.

The vertical arrangement of the switching shaft 10 which per se is not absolutely necessary for the invention offers among other advantages that the hot oil vapours ascend in 35 a direction perpendicular to the contacts, a condition likewise of great importance for the rapid extinction of the arc.

In this construction the spring 25 serves 40 to press the contacts against each other, and for this purpose it is necessary to mount the spring 25 so that, in the closed position of the switch, it has an initial tension in the closing direction of the contacts. For adjusting this pressure the screw 27 is arranged in accessible 45 position for operating it by removing a cap 28. By loosening the screw 27 the contact member is slightly raised and the resilient contact pieces 4 are more strongly compressed and the pressure of the contacts against each 50 other is increased.

Any objectionable strains due to shocks, more particularly before the completion of the switching movement, are prevented by special means which resiliently arrest the 55 moving parts and exert a brake action on the same, such means being hereinafter more fully described.

In another modification of the invention (Fig. 3) 3 denotes the switch casing, 7 the 60 hollow shaft of insulating material carrying the contact member, 8' the upper clamping sleeve, 10 the switching shaft, and 11 and 11' the two part casing fixed to the cover, 13 denotes the part secured to the switching 65 shaft and carrying at its bottom side the

teeth 14'' of the clutch, 15 denotes a part surrounding the switching shaft and journaled in the casing 11 by a ball bearing 16 and carrying at its top side the teeth 14' of the clutch 14, while its bottom end is 70 provided with gear teeth 18. The gear teeth 18 engage a toothed segment 20 operated by a pulling device 23. The spring 25 is arranged exteriorly of the parts 13 and 15 and one of its ends is secured to the part 13 and the other end to the part 15. The parts 13 and 15 are provided with central recesses in which another spring 30 is arranged, one of its ends being attached to the part 13 and the other end to the part 15. 75

The operation of this construction is similar to that described in connection with Fig. 1 in as much as the movement transmitted to the part 15 by the pulling device 23 tensions the spring 25 and enables the bottom teeth 14' of the clutch to accumulate energy in the driving part until the teeth 14' engage the teeth 14''. After the one part of the clutch has engaged the other part the entire energy is suddenly transmitted to the switching shaft 10 and the contact member is caused to swing about at a high speed. 80

The object of the spring 30 of this form is to produce the contact pressure in the position of rest and with this object in view the spring has a suitable initial tension. For this reason the spring 25 may not be under tension while the switch is in its closed position, the accumulating action of the spring 25 can be still better utilized in this 90 form than in the form shown in Fig. 1. For the better understanding of the action of the spring 25 it may be said that the spring 25 is so proportioned that the winding power required for putting it under tension is smaller than the winding power necessary for starting the contact member having the inertia of the switching disc and the parts 7, 8, 9, 10 connected therewith. 95

The means for producing a brake action 100 on the switching movement may be constructed in various ways. According to the invention the brake on the movable parts is produced in such a manner that the action takes place in steps. The braking action 105 on the driving parts takes place first and then on the driven parts. This is made possible by the above described construction of the clutch 14 since the lost motion (*s*) between the clutch teeth (14' and 14'') permits, during the application of the braking action on the driving parts, continued movement and separate braking action of the 110 driven parts. 115

In the form of the braking device for the driving part shown by way of example in Fig. 4 and in Fig. 6, 15 denotes the part of the driving mechanism provided with gear teeth 18 and embracing the shaft 10. 21 denotes the toothed segment of the lever 20 on 120

which the pulling device 23 acts. 22 denotes the pivot pin of the lever 20; on the pin 22 a lever 35 is pivoted, the hub of which carries teeth 36 coming into engagement with teeth 37 on the hub of the lever 20 after having moved through the space t . A projection 39 provided at the end of the lever 35 engages with projections 40 on rods 43, the latter being adapted to slide longitudinally in a support 42. Coiled springs 48 are interposed between discs contacting with the support 42 and discs 46 locked on the rods 43 by means of nuts 45.

In the position shown the driving element 15 has completed the greater part of its stroke and the teeth 37 have just come into contact with the teeth 36. As the movement continues the end of the lever 35 is moved to the left together with its projection 39 so 20 that the springs 48 are compressed and exert a brake action until the movement has ceased.

The driven part of the switch drive however, moves still further under the action of the spring 25 owing to the lost motion (s') 25 now existing between the rear of the driving teeth and the front of the driven teeth 14" and will be arrested only directly before having been moved through the entire angle s' (Fig. 2) by a separate braking device. 30 This braking device consists for instance of a plate spring 50 (Fig. 3) secured to a support 51 on the cover 3 of the switch casing and striking near the end of the switching movement against a pin 52 fixed to the part 35 9, whereby the movement of the driven part is fully stopped.

The time-way graph shown in Fig. 5 clearly illustrates the entire motions of the drive and the braking of driving and the driven 40 part of the high voltage oil switch.

The arc marked *a* illustrates the motion of the driving part and the arc marked *b* illustrates the motion of the driven part.

The driving part first moves through the 45 angle s . This movement, during which the energy of motion is accumulated in the moving masses of the driving part and in the tension of the spring 25, is represented by the line *k*. The adjacent line marked *l* represents the state of motion from the moment at which the clutch 14 is thrown into operation to the moment at which the clutch 36 is thrown into operation whereby a movement through the space or angle t has taken place. The line 50 *m* illustrates the brake action up to the moment at which the driving parts are stopped.

In the motion represented by the line *b* *n* represents the movement from the moment at which the clutch 14 is thrown into operation up to the moment at which the clutch 36, 55 37 is thrown into operation. During this entire movement power is transmitted to the shaft 10. The line *o* illustrates the continued movement of the contact member under the tension of the spring 25, and the line *p* rep-

resents the braking of the driven part by the plate spring 50. As will be seen, the movement of the driving part requires nearly the same time as the movement of the driven part, but with a phase difference which approximately corresponds to the time required for moving through the angle s .

The entire brake mechanism may be attached to the cover 3 of the oil switch with or without a casing, as shown in Fig. 6.

By the above described driving mechanism for oil switches, high switching speeds may be attained by means of comparatively small switching forces. Besides this condition, according to the invention at the same time a 80 notable reduction of the masses to be accelerated is secured by the combined action of the accumulation and the reduced masses, the rapidity of the switching proper is further increased to a surprising extent and the dependability in operation and the efficiency of the switch is increased.

What I claim is:

1. In a high voltage oil switch the combination of stationary contacts a rotatable contact member adapted to cooperate with the stationary contacts a driving element for such contact member a driven element connected to such contact member a coupling interposed between and operatively connected with the said driving element and driven element and means for transmitting motion energy to the driving element, such coupling comprising a two part clutch having lost motion, a power accumulating spring and another spring adapted to press the contact member against the said stationary contacts the latter spring being located in a recess in the said two part clutch.

2. In a high voltage oil switch the combination of stationary contacts a rotatable contact member adapted to cooperate with the stationary contacts a driving element for such contact member a driven element connected to such contact member a coupling interposed between and operatively connected with the said driving element and driven element and means for transmitting motion energy to the driving element, such coupling comprising a clutch having lost motion and a resilient element and means for braking first the driving part of the said clutch and afterwards the driven part of the clutch.

3. In a high voltage oil switch the combination of stationary contacts a rotatable contact member adapted to cooperate with the stationary contacts a driving element for such contact member a driven element connected to such contact member and a power accumulating coupling interposed between and operatively connected to the said driving element and driven element and means for braking step by step the moving masses such means comprising a lever pivoted to the said driving element and springs adapted to act on

such lever whenever the driving element reaches a predetermined position.

4. In a high voltage oil switch the combination of stationary contacts a rotatable contact member adapted to cooperate with the stationary contacts a driving element for such contact member a driven element connected to such contact member a coupling interposed between and operatively connected with the said driving element and driven element and means for transmitting motion energy to the driving element, such coupling comprising a clutch having lost motion and a resilient element and means for braking first the driving part of the said clutch and afterwards the driven part of the clutch the means for braking the driven part comprising a spring fixed in the casing and a pin fixed to a driven part the said spring and pin being adapted to come into engagement with each other after the driven part continues its movement independently of the driving element.

In testimony whereof I affix my signature.
